JOHN W. McCULLOH, OF BELLFLOWER, CALIFORNIA, ASSIGNOR OF ONE-HALF TO IRBA
E. McCULLOH, OF LONG BEACH, CALIFORNIA

FOLDING CHAIR

Application filed October 13, 1930. Serial No. 488,434.

My invention relates to and has for its purpose the provision of a chair of simple, substantial and inexpensive construction, particularly adapted, although not necessarily, for beach and camp use, and structurally characterized in such manner as to be rendered adjustable with the utmost ease and dispatch to comfortably support a person in various seated and reclining positions and 10 at widely different elevations from the ground, all while enabling the chair to be readily folded into a compact flat parcel for transportation and storage.

I will describe only one form of chair embodying my invention.

In the accompanying drawings,

Figure 1 is a view showing in plan one form of folding chair embodying my invention, adjusted to support a person substantially at the ground level;

Figure 2 is a view showing in side elevation partly broken away, the chair in the same position of adjustment illustrated in Figure 1;

Figures 3, 4 and 5 are views similar to Figure 2 and illustrating various positions of adjustment of the chair;

Figure 6 is a view of the chair in side elevation, and illustrating the manner in which 30 the several sections of the chair are associated in a partially folded position of the chair; and

Figure 7 is a view in side elevation illustrating the chair in completely folded position.

Referring specifically to the drawings, wherein similar reference characters indicate similar parts throughout the several figures, my invention comprises several sections, in 40 the present instance five in number, designated, respectively, 10, 11, 12, 13 and 14, and constructed of wood or other suitable material.

The section 10 constitutes a main frame and comprises a pair of longitudinal members 15, 15, connected in spaced parallel relation by series of transverse slats 16 and 17, the series of slats 16 being secured to one side edge of the members and extending along 50 the latter from one end thereof, and the se-

ries of slats 17 being secured to the opposite side edge of the members and extending along the latter from the opposite end thereof.

In the position of the chair shown in Figures 2, 3 and 4, the series of slats 16 are adapted to form a seat S, whereas in the position of the chair shown in Figure 5, the series of slats 17 are adapted to form a back rest B, so that it may be broadly stated that the main frame or section 10 is provided with 55 a seat portion and a back rest portion disposed in the present instance on reverse sides and at opposite ends of the frame.

Intermediate its ends and adjacent the innermost one of the slats 16, the section 10 has 65 mounted thereon the section 11 constituting a back rest B' which in the positions of the chair shown in Figures 2, 3 and 4 is adapted to co-act with the seat S. The section 11 is composed of a pair of longitudinal members 70 18, 18, connected in parallelism by a series of slats 19 to form a rigid frame which is pivoted on the section 10 by means of a rod 20 extending through the longitudinal members 15, 15, and 18, 18, of the sections 10 75 and 11, respectively.

The section 11 is thus rendered angularly adjustable on the section 10 to occupy various open positions in which it co-acts with the seat S to form the back rest for the latter, 80 and to occupy a folded position wherein it is disposed parallel to the section 10 with the longitudinal members 18 positioned within the longitudinal members 15.

The section 11 carries the section 12 which 85 constitutes a propping element P also in the form of a frame having a pair of longitudinal members 21—21 connected in parallelism by an intermediate transverse member 22 and an end transverse member 23. The section 12 90 is pivotally mounted on the section 11 intermediate the ends of the latter, by means of a rod 24 which extends through the members 18—18 and 21—21 of the sections 11 and 12, respectively.

The section 12 is adapted to be folded into the section 11 so that the members 21—21 of the section 12 are disposed within and parallel to the members 18—18 of the section 11. The end transverse member 23 of the section 12 is 95 100

extended beyond the members 21—21, so as to project across the longitudinal members 15—15 of the section 10 to provide lugs 25—25 which are adapted to engage with notches 26 5 formed at corresponding intervals along the longitudinal members 15—15 for co-action with the notches in enabling the section 12 to function as the propping element in supporting the section 11 in various positions of 10 angular adjustment relative to the seat S.

The section 13 constitutes a support on the section 10 for elevating the forward end of the latter and hence the seat S, and comprises legs 27—27 connected in parallelism by slats 15 28 to form a rigid frame pivotally mounted on the forward end of the section 10 by means of a rod 29 extending through the legs 27—27 and through the longitudinal members 15—15 of the section 10, to the end that the section 20 13 will be foldable to dispose its legs parallel to and within the members 15, 15 of the section 10.

The section 14 broadly constitutes a second seat S' adapted to co-act with the back rest 25 B in another position of the chair, and comprises a pair of members or legs 30—30 connected in parallelism by slats 31 and pivoted on the section 10 intermediate the ends of the latter and adjacent the innermost one of 30 the series of slats 17, by means of alined pins 32 extending through the members 15—15 and 30—30 of the sections 10 and 14, respectively. The section 14 is thus rendered adjustable to occupy a folded position parallel 35 to the section 10 and an open position for use as the seat S' in the position of the chair shown in Figure 5, or for use as supporting legs similar to the section 13 when the chair is adjusted to the position shown in Figure 3.

40 The members or legs 30—30 of the section 14 are constructed to provide hooks 33—33 at one extremity, for hooked engagement with the lugs 25—25 of the section 12, so as to co-act with the lugs when engaged with the innermost ones of the notches 26, in supporting 45 the section 14 in seat forming position under the weight of an occupant when the chair occupies the position of adjustment shown in Figure 5.

50 With the sections of the chair adjusted to the position shown in Figures 1 and 2, the section 10 is adapted to rest flatwise on the ground so that the seat S is disposed uppermost for use with the back rest B' disposed 55 at the desired angle for co-action with the seat S in supporting a person in any one of several reclining positions dependent on the adjustment of the propping element P or section 12 relative to the notches 26—26. It 60 will be clear that in this position of the chair, the sections 13 and 14 are folded underneath the section 10 so as not to interfere with the resting of the latter flatwise upon the ground.

In the position of the chair shown in Figure 3, the section 13 has been moved to its open

position to form a support or legs to elevate the forward end of the seat S, whereas in the position of the chair shown in Figure 4, both the sections 13 and 14 have been moved to open position to act as supports for elevating both the forward and rear ends of the seat S so that the latter is substantially horizontal. It will be clear that in any of the above described positions of the chair the back rest B' can be readily adjusted to the inclined position most suitable for the comfort of the occupant of the seat S.

In the event that a chair of greater height than that provided by the aforementioned adjustments is desired, the section 10 is inverted from its former position and the section 13 folded, after which the hooks 33—33 of the section 14 constituting the seat S' are engaged with the lugs 26—26 of the section 12 constituting the propping element P, as shown in Figure 5, so that the seat S' will be supported for use in co-action with the back rest B in supporting a person in a comfortable seated position.

When the chair is to be stored or transported, the several sections 11, 12, 13 and 14 are folded with respect to the section 10 in the order shown in Figure 6; and when the sections are completely folded as shown in Figure 7, the chair will form a compact and flat parcel of rectangular outline so as to occupy a minimum space.

Although I have shown and described only one embodiment of my invention, it is to be understood that various changes and modifications may be made within the spirit of the invention.

I claim as my invention:

1. A chair comprising a plurality of sections, certain of which form seats and others back rests for co-action with the seats, means for connecting the sections for adjustment to occupy different relative positions wherein the seat forming sections and the respective back rest forming sections can be selectively disposed to provide chairs of different heights, means for maintaining the seat and back rest forming sections in one of said positions when adjusted to provide the chair of one height, and means for maintaining the seat and back rest forming sections in the other of said positions when adjusted to provide the chair of another height.

2. A chair comprising a main frame having a seat portion and a back rest portion on reverse sides, a back rest mounted on the main frame for co-action with the seat portion of the latter in forming a relatively low chair when the frame occupies one position, and a seat member adjustably mounted on the frame to occupy an angular position relative to the frame for co-action with the back rest portion of the latter in forming a relatively high chair when the frame is inverted.

from said position, and wherein the back rest and main frame function as legs.

3. A chair comprising a main frame having a seat portion and a back rest portion on 5 reverse sides, a back rest, means for mounting the back rest on the frame to occupy a folded position and an open position wherein the back rest co-acts with the seat portion of the frame to form a relatively low chair when 10 the frame occupies one position, means on the main frame and back rest co-acting to maintain the latter in open position, a seat member, means for mounting the seat member on the main frame to occupy a folded position 15 and an open position wherein the seat member co-acts with the back rest portion of the frame to form a relatively high chair when the frame is inverted from said position, and means for maintaining the seat member in 20 open position.

4. A chair comprising a main frame having a seat portion and a back rest portion on reverse sides, a back rest, means for mounting the back rest on the main frame for angular 25 adjustment relative to the seat portion of the frame to co-act therewith in forming a relatively low chair when the frame occupies one position, co-acting means on the frame and back rest for supporting the latter in various 30 positions of angular adjustment, a seat member, means for mounting the seat member on the main frame to occupy a folded position and an open position wherein the seat member co-acts with the back rest portion 35 of the frame to form a relatively high chair when the frame is inverted from said position, and means on the seat member co-acting with the first means to support the seat member in open position.

40 5. A chair comprising a main frame having a seat portion and a back rest portion disposed respectively on opposite sides and at opposite ends of the frame, a back rest pivotally mounted on the main frame intermediate 45 the ends of the latter for co-action with the seat portion of the frame in forming a chair when the frame is disposed in one position, means for supporting the back rest in position to co-act with the seat portion of 50 the frame, a seat member pivotally mounted on the main frame intermediate the ends of the latter for co-action with the back rest portion of the frame in forming a different type of chair when the frame is inverted 55 from said position, and means for supporting the seat member in co-acting relation with the back rest portion of the frame.

6. A chair comprising a main frame having a seat portion and a back rest portion disposed respectively on opposite sides and at opposite ends of the frame, a back rest pivotally mounted on the main frame intermediate the ends of the latter for co-action with the seat portion of the frame in forming a chair when the frame is disposed in one posi- 65

tion, means for supporting the back rest in position to co-act with the seat portion of the frame, a seat member pivotally mounted on the main frame intermediate the ends of the latter for co-action with the back rest portion of the frame in forming a different type of chair when the frame is inverted from said position, and means on the seat member co-acting with the first said means to maintain the seat member in co-acting relation with the back rest portion of the frame.

7. A chair comprising a main frame having a seat portion and a back rest portion disposed respectively on opposite sides and at 80 opposite ends of the frame, a back rest pivotally mounted on the main frame intermediate the ends of the latter for co-action with the seat portion of the frame in forming a chair when the frame is disposed in one position, a propping element on the back rest and notches in the main frame with which the propping element engages to support the back rest in co-acting relation to the seat portion of the frame, a seat member pivotally 85 mounted on the frame intermediate the ends of the latter for co-action with the back rest portion of the frame in forming a different type of chair when the frame is inverted from said position, and means on the seat member co-acting with the propping element when engaging said notches, to maintain the seat member in co-acting relation with the back rest portion of the frame.

8. A chair comprising a main frame having a seat portion and a back rest portion disposed respectively on opposite sides and at opposite ends of the frame, a back rest pivotally mounted on the main frame intermediate the ends of the latter for co-action with the seat portion of the frame in forming a chair when the frame is disposed in one position, a propping element on the back rest and notches in the main frame with which the propping element engages to support the back rest in co-acting relation to the seat portion of the frame, a seat member pivotally mounted on the frame intermediate the ends of the latter for co-action with the back rest portion of the frame in forming a different type of chair when the frame is inverted from said position, and lugs on the propping element and hooks on the seat member co-acting to maintain the seat member in co-acting relation with the back rest portion of the frame when the propping element engages said notches.

9. A chair comprising a main frame having a seat portion and a back rest portion, a back rest mounted on the frame for adjustment to occupy an open position wherein the back rest co-acts with the seat portion of the frame to form a relatively low chair when the frame is disposed in one position, means for main- 130

taining the back rest in open position, a seat member mounted on the frame for adjustment to occupy an open position wherein the seat member co-acts with the back rest portion of the frame to form a relatively high chair when the frame is disposed in another position, and means for maintaining the seat member in open position.

JOHN W. McCULLOH.
